UNITED STATES PATENT OFFICE.

ALFRED N. NELSEN, OF LONG BEACH, CALIFORNIA.

TENT FOR CAMPING.

Application filed March 24, 1919. Serial No. 284,845.

To all whom it may concern:

Be it known that I, ALFRED N. NELSEN, a citizen of the United States, residing at Long Beach, in the county of Los Angeles 5 and State of California, have invented a new and useful Tent for Camping, of which the following is a specification.

The invention relates to improvements in tent construction and tent accessories for 10 camping; and consists of the new and useful features and in the improved construction, combination and arrangement of parts the purpose of which will be apparent to those skilled in the art, from a consideration of the preferred form of construction 15 herein shown.

The principal object of this invention is to provide a tent with folding and disconnecting parts which may be assembled into 20 a compact bundle of small size; and which parts may be easily and quickly re-assembled into a substantial tent which will be spacious, comfortable and convenient.

Another object of this invention is to provide a tent with removable back, front and 25 side curtains, that will be especially adapted for open air sleeping or resting.

Another object of this invention is to provide a rigid and substantial support for 30 the canopy of the tent when the back, front and side curtains are removed, which support has a firm anchorage in the sand or ground.

Another object of the invention is to provide on the canopy support a table which 35 when not in use may be elevated to a position where it will be entirely out of the way.

Another object of this invention is to provide on the upper end of the canopy support 40 a receptacle in which articles of value may be placed.

Other objects, advantages and features of invention will appear from the drawings, the subjoined detail description and 45 the appended claims.

The drawings illustrate the invention.

Figure 1 is a perspective view of three of the tents embodying the elements of this invention, erected on the seashore.

50 Fig. 2 is a central vertical section through a tent; the staff of the canopy support, table and anchor not being in section.

Fig. 3 is a plan view of the sleeping or 55 rest mat removed from the tent.

Fig. 4 is a section on the line x^4-x^4 of Fig. 3 showing at one end the adjustable

head support and means for holding the body of the mat in a flattened position.

Fig. 5 is a plan view of the frame associated with the mat, part of the spacing 60 rods being broken away.

Fig. 6 is a side elevation of the mat frame in folded position.

Fig. 7 is a section taken on the line x^7-x^7 of Fig. 3. 65

Fig. 8 is a section taken on the line x^8-x^8 of Fig. 2, with parts omitted, showing the table in plan view.

Fig. 9 is a section taken on the line x^9-x^9 of Fig. 8. 70

Fig. 10 is a side view of the table removed from the staff and in folded position.

Fig. 11 is a section taken on the line $x^{11}-x^{11}$ of Fig. 2 showing the canopy support 75 with the canopy removed.

Fig. 12 is a section taken on the line $x^{12}-x^{12}$ of Fig. 11, parts broken away and parts omitted and an altered position of the canopy supporting arms shown by dotted 80 lines.

Fig. 13 is a section taken on the line $x^{13}-x^{13}$ of Fig. 2 showing the joint of the canopy staff.

Fig. 14 is a perspective view of the bottom part of the canopy staff showing the 85 means for driving and anchoring the staff in the sand or ground.

Fig. 15 is an enlarged view of what is shown in the upper left hand corner of the 90 tent in Fig. 2.

Fig. 16 is a side elevation of the hand 95 piece for attaching to the socket end of the staff when the latter is to be screwed into the sand or ground.

In detail, the tent is supported by the staff 2 which consists of the lower and upper parts 3 4 that are connected by the screw and socket joint 5.

Adjacent the lower end of the part 3 there 100 is secured the auger 6 which is preferably constructed of sheet metal cut to form an extended helical blade with an inner flange 7 which may be nailed or riveted to the part 3; and when this auger 6 is to be driven into 105 the sand or ground, the hand lever 8 shown in side elevation in Fig. 16 and in dotted lines in Figs. 2 and 13 has its threaded extension 9 screwed in the socket on the upper end of the part 3 forming thereby an 110 auger which may be used to drive the helical end of said post into the sand or ground.

In ordinary sand, however, such as is found at the sea shore, the hand lever is not required to sink the part 3 into the sand a sufficient distance to firmly hold the staff, as such operation may be easily accomplished without such aid.

The idea of securing a helical strip of metal adjacent the bottom of a part for the purpose of sinking and holding the part in the ground is broadly new and basic in principle; and I do not limit myself to any specific construction in that respect, as the invention is broadly new and admits of various changes and modifications, a right to 15 such of which as do not depart from the spirit of the invention.

After the part 3 is embedded in the ground or sand and the handle 8 removed, the part 4 is attached to the part 3 by means 20 of the screw joint 5.

The upper end of the staff has the reduced portion 10 over which is fitted the tubular flange 11 of the receptacle 12.

To the bottom 13 of the receptacle 12, there 25 are secured one wing each of the eight hinges 14 spaced apart radially from the center of said receptacle.

To the other wing of each of said hinges 14 are secured the arms 15 which normally 30 hang at right angles to the bottom of said receptacle and folded down toward one another, as indicated by dotted lines in Fig. 12.

When the arms 15 are extended to support the top canopy 16 of the tent, they are 35 secured to the bottom 13 of the receptacle 12 by means of the bolts 17 and thumb nuts 18; said arms being adapted to extend radially from a common center and spaced equal distances apart. In the drawings this top canopy formation is shown as being square; but 40 it may be made round, oblong or any other shape for its purpose without departing from the spirit of this invention.

The arms 15 are preferably of a length 45 which when extended their outer ends will form an imaginary square, or any other shape that may be desired, according to the lengths of the different arms. To these outer ends are secured the buttons 19 and 20 by 50 which the tent curtains 21 and 22 and 16 are secured to the arms; said curtains preferably made of canvas.

The curtain 21 encloses the back and sides of the tent, the top edge being secured to 55 the buttons 19 and 20 as stated.

The bottom edge of the piece 21 is turned up and secured to form the pockets 24 around the bottom edge, said pockets adapted to be filled with earth or sand, the weight 60 of which is designed to hold the curtain 21 in place without additional fastenings.

The part 22 is adapted to be used as a closure of tent front, and it is provided with 65 pockets adjacent its bottom edge to contain stay weights. It is buttoned to the arms in

a similar manner and is provided with the buttons 23 by means of which it may be secured to the part 21.

The top canopy 16 is provided with the opening 25 at its center and adapted to fit 70 over the end of the extension staff 2, and to rest upon the upper end of the cylindrical flange 11. It is buttoned to the radial arms 15, its edges 26 overlapping the sides 75 21 and 22.

The receptacle 12 has in its outer wall 27 the cut away portion 28 having the raised portion 29 which contacts with the under side of the top canopy 16; the cut away portion forming an opening through which articles 80 may be placed in the receptacle 12.

The tent is provided with a rest or sleeping mat 30 formed of collapsible parts, the body 31 being of air tight material, adapted to be inflated through the tube 32, as shown 85 in Fig. 3. In the center of said body is formed the opening 33 large enough to fit around the staff 2; and the mat is placed in position as soon as the staff 2 is secured in place in the ground and before the other 90 parts of the tent are erected.

The mat is held in place by means of the collapsible frame 34 having the head rest 35. This frame is formed of the paralleling longitudinal bars 36 formed in two parts 95 pivoted together by the pins 38, and these bars are spaced apart at one end by the rod 37, and pivotally connected to these ends of the bars are one end of the arms 39 having near their center the bar 40 and to which 100 bar are pivotally connected one end of the short legs 41.

Pivots mounted on the rod 37 is one of the notched latch bars 42 the notches of which are adapted to engage the pins 43 on 105 the short legs 41 to hold the head rest 35 in any desired position.

As shown in Figs. 2 and 4, the mat 30 has near its forward end and on the underside thereof the cut away portion 41' which permits the forward end of the frame 34 to be inserted in the pocket 45, and the bars 36 in the side pockets 46 and 47, as shown in 110 Figs. 2, 3, 4 and 7.

If desirable, the interior of the mat 30 may be provided with the wall 48 to divide 115 the mat into a plurality of connected compartments.

Before the tent is erected and immediately after the mat 30 is in place over the staff 2, a table 49 having an opening 50 substantially the diameter of and fitting the staff 2 is placed thereon. After the tent is erected this table is adapted to be moved up or down on the staff 2.

The table 49 is formed of the parts 51 and 52 which are joined together by the hinges 53 on the top side of the table; and by means of these hinges and the weight of 125 the parts 51 and 52 the lower edge of the 130

table around the hole 50 will pinch against the post 3 and hold the table in any desired position.

In order to furnish a larger gripping area 5 to the table on the post 3 extensions 54 and 55 can be secured to the parts 51 and 52 so that these extensions will contact with the staff and hold the table against downward movement.

10 Any material placed upon the table 49, such as books, lunch or packages will add their weight to additionally pinch the contacting edges thereof more firmly against the staff; so that when weighted the table is 15 locked against downward movement until the pressure is released by lifting on the parts 51 and 52. In this manner the table may be positioned at any desired height on the staff.

20 As shown in the three views in Fig. 1, the tent may be entirely enclosed as in A: or open except the curtain 22 which is used as a sun shade or wind break, as in B; or it may be used entirely open, except for the 25 top canopy, as in C.

This invention admits of modifications and changes, and the right is reserved to all such alterations as are purely mechanical equivalents in structure and operation 30 to those herein disclosed.

I claim:

1. In a tent, an anchored staff; a receptacle on the top of said staff; radial arms secured to said receptacle; and a canopy over said arms said receptacle being provided with a wall having cutaway portions, the upper edges of said wall contacting with the canopy and forming an enclosure; access to which may be had through said cutaway portions.

2. In a tent, an anchored staff; a receptacle on the top of said staff; radial arms secured to said receptacle; a canopy over

said arms; said receptacle being provided with a wall having cutaway portions, the 45 upper edges of said wall contacting with the canopy and forming an enclosure; access to which may be had through said cutaway portions; and curtains under said canopy attached to said arms.

3. In a tent, an anchored staff; a receptacle on the top of said staff; arms secured to said receptacle; side curtains having their top edges attached to the outer ends of said arms; pockets on the bottom edges of said 50 sides whereby said sides may be weighted; and a canopy over said staff and attached to said arms; said receptacle functioning with said canopy to form an enclosure.

4. In a tent, a staff; a receptacle on the 55 top of said staff; arms hinged to the bottom of said receptacle so that said arms can fold toward one another; bolts in the bottom of said receptacle for holding said arms in a plane parallel with the bottom of said 60 receptacle; and a canopy and curtains attachable to said arms; said receptacle being provided with a wall having cutaway 65 portions, the upper edges of said wall contacting with the canopy and forming an enclosure; access to which may be had through 70 said cutaway portions.

5. In a tent, a staff supporting said tent; an anchor supporting said staff; a folding table on said staff; said table hinged so that 75 its downward pressure pinches said staff and prevents downward movement of said table.

In testimony whereof, I have hereunto set my hand at Los Angeles California, this 80 13th day of March 1919.

A. N. NELSEN.
